HAND HELD POWER TOOL OR THE LIKE

Dallas R. Humphrey, North St. Paul, and Logan W. Johnson, Minnetonka, Minn., assignors to Kroy Industries Inc., Stillwater, Minn., a corporation of Minnesota

Filed Aug. 9, 1968, Ser. No. 13,078

Term of patent 14 years

Int. Cl. D8—02

U.S. Cl. D8—61

FIGURE 1 is a side view of a hand held power tool or the like embodying the ornamental design of this invention;

FIGURE 2 is a top view thereof;

FIGURE 3 is a bottom view thereof;

FIGURE 4 is an end view thereof, as seen from the right end of FIGURE 1; and

FIGURE 5 is an end view thereof, as seen from the left end of FIGURE 1.

The dominant features of our design reside in the portion shown in full lines.

We claim:

The ornamental design for a hand held power tool or the like, substantially as shown and described.
